UNITED STATES PATENT OFFICE.

ELMER E. CRONE, OF LOUISVILLE, KENTUCKY.

MONEY-DRAWER AND LOCKING DEVICE THEREFOR.

No. 907,223.

Specification of Letters Patent.

Patented Dec. 22, 1908.

Application filed March 20, 1908. Serial No. 422,211.

To all whom it may concern:

Be it known that I, ELMER E. CRONE, a citizen of the United States, residing at Louisville, in the county of Jefferson and State of Kentucky, have invented certain new and useful Improvements in Money-Drawers and Locking Devices Therefor, of which the following is a specification.

My invention relates to improvements in 10 merchants' cash or money drawers, and similar articles.

One of its objects is to provide an automatic locking mechanism for such articles, which can be readily and quickly opened by 15 one familiar with the combination, but not readily opened by a person without knowledge of the combination.

Another object is to provide simple and 20 readily manipulated mechanism whereby the combination may be changed.

Another object is to provide an alarm 25 adapted to be sounded either when the drawer is opened or when an attempt is made to open the drawer, or both, and ready means for changing the alarm sounding mechanism to accomplish the desired result.

Another object is to provide a simple, reliable and inexpensive mechanism to accomplish the above purposes.

30 It further consists in certain details of form, combination and arrangement, all of which will be more fully set forth in the description of the accompanying drawings, in which;

35 Figure 1 is a top plan view of a money drawer embodying my improvements. Fig. 2 is a bottom plan view of the drawer, attaching plate and under side of a counter. Fig. 3 is a perspective view of the latch to trip 40 the hammer of the alarm or gong. Fig. 4 is a perspective view of the alarm hammer and its supporting bracket. Fig. 5 is a perspective view of one of the finger bars by which the lock mechanism is actuated. Fig.

45 6 is a perspective view of the alarm actuating plate or lever, which carries the latch, Fig. 3. Fig. 7 is an enlarged central section on line $v-v$ of Fig. 1 through the drawer and counter to which it is attached, and showing 50 the parts in position to lock the drawer. Fig. 8 is a view similar to Fig. 7 showing the parts in the opposite position. Fig. 9 is a perspective view of one of the rocking beams.

Fig. 10 is a perspective view of one of the 55 sliding bars. Fig. 11 is an inverted per-

spective view of the dogging or locking mechanism stationarily located beneath the counter.

In the accompanying drawings, representing a convenient form of my improved device, A represents the counter, show-case or similar stationary article to the underside of which the money drawer is to be attached. I preferably provide an attaching plate, A', which is supplied with the drawer, and is provided at its edges with guides or ways, a, which are engaged by projecting ribs, a', carried by the drawer, and by means of which the drawer is enabled to slide from the closed to the open position. The lock mechanism 60 may thus be assembled and the respective parts attached to the drawer and plate, A', at the factory, and the drawer placed in position for use by securing the plate, A', in the desired position beneath the counter. 70

To the under side of plate A' at the rear end thereof is secured a rectangular frame, B, to which at b is pivoted a plate C having two teeth c c' and a lip c² which enters between the edge b' of plate B and the plate 75 A', and thereby limits the movement of plate C.

The drawer D is provided at the forward end with compartments, d, to receive bills and coins, or if desired with a secondary contained drawer or sliding tray sliding above the compartments d.

80 Within the drawer D and at the rear thereof is secured a rectangular frame E, preferably composed of stamped sheet metal plates united together by means of projecting lugs entering corresponding recesses and then bent over to retain the plates in place. The frame E is secured to the bottom, d', and rear wall, d², of the drawer by flanges, 85 e. The screws which pass through the flanges e into the bottom also pass through and lock in place a bottom plate, E', having a central rectangular opening e' which registers with a similar shaped opening in the bottom of 90 the drawer. 95

100 Within the frame E are arranged side by side a series of sliding plates, F, preferably about five in number. The plates F are widened at the base f so that when assembled they entirely close the opening e' being held in place against the bottom plate by reason of their forward ends f' projecting through a slot e² in the frame E, and further by ears f² which project through the opening e' and 110

have attached thereto the arms or bars G. These arms lie close to the under side of the drawer bottom, and are held thereto by a strap g through which arms G are free to move endwise. The forward ends of arms G have attached thereto finger plates g', one or more of which are adapted to be grasped by the fingers of the operator in the act of drawing the drawer to the open position, the 10 arms G first moving forward carrying with them the plates F as far as the opening e' will permit the ears f² to travel, after which if the proper finger plate or plates have been grasped the drawer will commence to open.

15 The plates F are normally held in the position Fig. 7 by springs f³ attached to a cross rod f⁴. The upper edges of plates F are provided with notched openings f⁵ into which project the depending arms h of the rocking bars H, a series of which are pivoted vertically above the plates F by means of a cross bar h'. The rocking bars H are each provided with horizontal arms h², h³ which are respectively depressed and elevated by the 20 rocking movement imparted to bars H by the movement of the plates F.

25 The top plate of frame E is provided with a series of holes e⁴ arranged in two separate rows above the ends of arms h², h³.

30 I represents a partition plate located above the bars H and provided with a series of holes i to register with the holes e⁴. The holes e⁴ and i serve as sockets or lateral supports to support in a vertical position a 35 series of pins K K', the pins K being those seated in the row of sockets beneath the tooth c, and those indicated in the drawing by K' being the pins seated in the row of sockets beneath tooth c'. Said pins are free to move vertically by gravity or other force 40 imparted thereto, and at their lower ends rest upon the ends of arms h² h³. The forward movement of any one of the plates F serves to rock the bar H in engagement 45 therewith, which through the arm h³ elevates the pin K' resting on arm h³, and at the same time permits the pin K resting on arm h² to descend by gravity, as is indicated in Figs. 7 and 8, in which Fig. 7 shows the 50 position of the parts before, and Fig. 8 the position of the parts after the bar F has been moved forward. The pins K K' are of such length that when in the position Fig. 7 the pins K will engage the tooth c of plate C, and pins K' are then in position to 55 clear the tooth c. When any one of the bars H having both a pin K and a pin K' in engagement with its arms h² h³ is rocked by pressure on its corresponding finger plate g', the pins K K' assume the position indicated 60 in Fig. 8, in which the pin K' engages the tooth c', which engagement is effected before the pin K has ceased to engage the tooth c. Thus in practice pressure by the 65 operator upon a finger plate g' to actuate a

bar H above which were arranged both a pin K and a pin K' would result in failure to release or open the drawer.

In practice one or more pins K are seated in the sockets over respective arms h² of bars H, say for instance in the first three sockets on the right in Fig. 1, of the upper row of sockets, and two pins K' are seated in the first two sockets at the left of the lower row, then an operator would fail to open the 75 drawer if he pressed the two left hand finger plates to actuate the pins K' which would dog the tooth c', and he would also fail to release the drawer unless he did press each of the three finger bars g' at the right hand 80 to actuate the pins K to disengage them from the tooth c. Thus one or more pins K may be variously arranged in the upper row of sockets in combination with one or more pins K' in the lower row of sockets to vary 85 as desired the combination required to open the drawer. The slight pivotal movement of plate C permitted by lip e² permits the pins K K' to simultaneously pass the teeth c c' when the drawer is pushed from the 90 open to the closed position.

A recess f⁶ in the forward end of each plate F permits the adjustment thereto of one or more studs or pins f⁷ the upper ends of which studs engage the rear face of a 95 plate L which is pivoted at l to ears e⁸ projecting from the frame E. The plate L is normally held in the position Fig. 7 by a spring l', and has an ear l² to which is loosely pivoted a latch bar L'. 100

M represents a lever pivoted at m to a bracket m' attached to the side of frame E. Lever M is normally held in the position Fig. 1 by a spring m², and has an ear m³ which is engaged by the notch l⁴ of latch 105 bar L' and is drawn forward until its beveled edge lifts latch bar L' releasing ear m³, which allows spring m² to return lever M to normal position.

M' represents a hammer at the free 110 end of lever M which strikes a gong N to sound an alarm. By seating a stud, f⁷ in the end of each plate F the plate L will be shifted to the position Fig. 8 and thereby sound an alarm upon pulling any- 115 one of the finger plates g' or by placing studs f⁷ in only a portion of the plates F² arrangement may be made to sound an alarm only when the finger bars necessary to open the drawer are operated, or arrangement 120 may be made to sound an alarm only when an unsuccessful attempt has been made to open the drawer.

P represents a tapered strip attached to plate A' in front of frame B to guide pins K 125 back to plate C when the drawer is closed.

The mechanism herein illustrated and described is capable of considerable modification without departing from the principle of my invention. 130

Having described my invention, what I claim is.

1. In a device of the character indicated, a stationary member, a plate having a plurality of teeth carried by said stationary member, a movable member, a frame carried by said movable member, said frame being provided with a plurality of sockets arranged in separate rows opposite the different teeth of said plate, a series of pins adapted to be selectively seated in separate sockets in position to engage the teeth of said plate, and a plurality of finger plates each adapted when actuated to cause an upward movement of a pin in one row and a downward movement of a pin in the other row of said sockets. 10
2. In a device of the character indicated, a stationary member, a plate having a plurality of teeth carried by said stationary member, a movable member, a frame carried by said movable member, said frame being provided with a plurality of sockets arranged in separate rows opposite the different teeth of said plate, a series of pins adapted to be selectively seated in separate sockets in position to engage the teeth of said plate, and a plurality of finger plates each adapted when actuated to cause an upward movement of a pin in one row and a downward movement of a pin in the other row of said sockets. 20
3. In a device of the character indicated, a stationary member, a plate having a plurality of teeth carried by said stationary member, a movable member, a frame carried by said movable member and provided with a series of holes in rows opposite separate teeth of said plate, a series of pins adapted to be selectively seated in said holes and adapted to engage the teeth of said plate, a series of rocking bars pivotally mounted beneath said holes, each rocking bar being adapted to cause an upward movement of a pin in one row and a downward movement of a pin in the other row of said holes, a series of finger plates in position to be grasped to move said movable member, and means connecting said finger plates with said rocking bars to rock said bars when the respective finger plates are passed. 30
4. In a device of the character indicated, a stationary member, a plate having a plurality of teeth carried by said stationary member, a movable member, a frame carried by said movable member and provided with a series of holes arranged in separate rows, a series of pins adapted to be selectively seated in said holes, and to engage the respective teeth of said plate, a series of rocking bars pivotally mounted beneath said holes, and each adapted to cause an upward movement 40
- of a pin in one row and a downward movement of a pin in the other row of said holes, a series of spring actuated sliding plates adapted to tilt said rocking bars, and a series of finger plates connected to said sliding plates and in position to be grasped to move said movable member. 70
5. In a device of the character indicated, a stationary member, a plate having a plurality of teeth carried by said stationary member, a movable member, a frame carried by said movable member and provided with a series of holes arranged in separate rows, a series of pins adapted to be selectively seated in said holes and to engage the respective teeth of said plate, a series of rocking bars pivotally mounted beneath said holes and each adapted to cause an upward movement of a pin in one row and a downward movement of a pin in the other row of said holes, a series of spring actuated sliding plates adapted to tilt said rocking bars, and a series of finger plates connected to said sliding plates and in position to be grasped to move said movable member, an alarm actuating mechanism, each of said sliding plates being provided with sockets, and one or more studs adapted to be selectively seated in said sockets and adapted to trip said alarm actuating mechanism when the sliding plates provided with studs are actuated. 80
6. In a device of the character indicated, a stationary member, a plate having a plurality of teeth pivotally attached to said stationary member and having a limited pivotal movement, a drawer adapted to slide relative to said stationary member, a frame carried within said drawer and provided with a series of holes, a series of pins adapted to be selectively seated in said holes, a series of rocking bars pivotally supported beneath said holes and each adapted to cause an upward movement of a pin in one row and a downward movement of a pin in the other row of said holes, a series of spring actuated sliding plates adapted to rock said rocking bars, and a series of finger plates connected to and adapted to actuate said sliding plates, and in position to be grasped to open said drawer. 90
7. In a device of the character indicated, a stationary member, a plate having a plurality of teeth pivotally attached to said stationary member and having a limited pivotal movement, a drawer adapted to slide relative to said stationary member, a frame carried within said drawer and provided with a series of holes, a series of pins adapted to be selectively seated in said holes, a series of rocking bars pivotally supported beneath said holes and each adapted to cause an upward movement of a pin in one row and a downward movement of a pin in the other row of said holes, a series of spring actuated sliding plates adapted to rock said 100
- 110
- 120
- 130

rocking bars, and a series of finger plates connected to and adapted to actuate said sliding plates, and in position to be grasped to open said drawer, a gong carried within 5 said drawer, a hammer to strike said gong, a latch to trip said hammer, a pivoted plate to actuate said latch overhanging one end of said sliding plates and adapted to be actuated by studs selectively seated in sockets 10 in said sliding plates.

8. In a device of the character indicated, a drawer, a series of sliding plates carried thereby and each provided with a socket to support a detachable stud, one or more studs 15 adapted to be selectively seated in said sock-

ets, a series of finger plates in position to be selectively pressed in opening said drawer, and adapted when pressed to actuate said sliding plates, an alarm, and mechanism for sounding said alarm, said alarm actuating 20 mechanism being adapted to be actuated by one or more of said studs when seated in any one of said sockets.

In testimony whereof I have affixed my signature in presence of two witnesses.

ELMER E. CRONE.

Correction in Letters Patent No. 907,223.

It is hereby certified that in Letters Patent No. 907,223, granted December 22, 1908, upon the application of Elmer E. Crone, of Louisville, Kentucky, for an improvement in "Money-Drawers and Locking Devices Therefor," an error appears in the printed specification requiring correction, as follows: In line 54, page 3, the word "passed" should read *pressed*; and that the said Letters Patent should be read with this correction therein that the same may conform to the record of the case in the Patent Office.

Signed and sealed this 19th day of January, A. D., 1909.

[SEAL.]

C. C. BILLINGS,

Acting Commissioner of Patents.
